UNITED STATES PATENT OFFICE

JACOB C. JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING ON SHOES

Application filed July 7, 1930. Serial No. 465,940.

This invention relates to machines for operating on shoes, and is herein illustrated as applied to an automatic heel-seat lasting machine of a type disclosed generally in 5 Letters Patent No. 1,583,044, granted on May 4, 1926 upon an application of C. H. Hoyt, except as to some features of the shoe support and its operating mechanism which are more particularly disclosed in Letters 10 Patent No. 1,558,737, granted on October 27, 1925 upon an application of R. F. McFeely. It is to be understood, however, that in its more general aspects the invention is not limited to machines of that particular type 15 nor to machines for lasting shoes.

Machines of the type disclosed in the above-mentioned Letters Patent comprise in their organization a power-operated shoe support or jack whereby the shoe is pressed 20 rearwardly against a heel band and is also pressed against a holdown which determines adjustably the location of the heel end of the sole or insole in relation to the plane of the heel-lasting wipers. Combined 25 with the means for thus operating the jack is also mechanism for closing the heel band inwardly against the opposite sides of the heel end of the shoe. In the operation of such machines it may sometimes happen, by 30 reason, for example, of improper adjustment of the holdown, that the shoe is so positioned as to oppose abnormal resistance to the operative movement of the wipers, as a 35 result of which the operation of the machine is stopped before it completes its cycle. Under such conditions it has been necessary heretofore for the operator, by the use of a lever applied to a wheel on the machine, to 40 complete the cycle of the machine manually. This is a slow and difficult operation and involves danger of damaging the shoe or of 45 breaking some part of the machine.

An object of the present invention is to 45 avoid such difficulties and disadvantages as above mentioned, and to this end the invention, in one aspect, provides novel means whereby the resistance to the operation of a machine, if excessive, may be readily and quickly decreased, for example, if the machine 50 is stopped under conditions such as

described, so that the machine may complete its movements and return the parts to their starting positions. For the purpose in view, as herein illustrated, a bell-crank lever whereby both the jack and the heel band are 55 operated to clamp the shoe is so constructed that one of its arms comprises two relatively movable parts which are normally held in a fixed relation to each other but may be 60 manually disconnected to permit relative movement between them such as to relax the pressure on the shoe and thus permit the shoe to yield so that the wipers can complete their operative movements. In the construction shown, moreover, automatic means 65 is provided for restoring the two parts of the lever to their normal fixed relation to each other in the continued operation of the machine.

The novel features of the invention, including various novel details of construction and combinations of parts, will now be more particularly described by reference to the accompanying drawings and pointed out in 70 the claims.

In the drawings,

Fig. 1 is a view, partly in side elevation and partly in vertical section, of a portion of a machine in which the invention is embodied, illustrating the positions of the parts when the machine is stopped by abnormal resistance to the movement of the wipers;

Fig. 2 is a view in side elevation of the mechanism provided for purposes of this invention and portions of the machine associated therewith, with the parts in their normal starting positions;

Fig. 3 is a view in front elevation of the parts shown in Fig. 2;

Fig. 4 is a view similar to Fig. 2, but illustrating the positions of the parts when the pressure on a shoe has been relaxed by the novel mechanism provided; and

Fig. 5 is a view partly in plan and partly in section showing the mechanism for operating the heel band to clamp the shoe.

Machines of the type illustrated comprise in their organization heel-lasting wipers 10 which are moved length-wise and laterally 100

of the shoe in an automatically determined cycle of operations of the machine to wipe the margin of the heel-end portion of the upper materials inwardly over a sole or in-
5 sole on the last, together with tacking mechanism 12, the construction of which is not illustrated in detail, for fastening the upper in lasted position. The wipers and the as-
10 sociated tacking mechanism in the machine herein shown are constructed as disclosed in Letters Patent No. 1,852,015, granted upon an application of mine on April 5, 1932. The wipers are operated by a path cam 14 formed in a cam wheel 16 fast on a shaft 18, 15 through connections including a roll 20 and a slide 22, as more fully disclosed in the last-mentioned Letter's Patent.

The shoe support or jack comprises a holder 24 mounted for swinging movements 20 about a shaft 26 rotatable in bearings in the frame of the machine, and a post 28 movable upwardly and downwardly in the holder and provided at its upper end with a pin 30 which enters the spindle hole in the last. 25 The post 28 is supported on a rod 32 which is also movable upwardly and downwardly and is provided at its lower end with a rack 34 in engagement with a pinion 36 fast on the shaft 26. Mounted for turning movement 30 on the shaft 26 is a pawl carrier 38 provided with a pair of pawls 40 arranged to engage a ratchet wheel 42 which is fast on the shaft for turning the pinion 36 and thus raising the jack post 28. By this mechanism 35 the heel-seat face of the shoe is pressed against a hold-down 44 which determines adjustably the height of the shoe and accordingly the relation of its heel-seat face to the plane of the wipers 10. For im- 40 parting to the pawls 40 their operative movement there is connected to the pawl carrier 38 a rod 46 on the upper end of which is secured a cylindrical member 48 which serves as a housing for a spring 50 45 interposed between the upper end of the member 48 and a plunger 52 on the lower end of a rod 54 which is slidable in the member 48. The rod 54 at its upper end is connected to a bell-crank lever 56 provided with 50 a gear sector 58 engaged by rack teeth formed on the lower face of a slide 60 pressed forwardly by springs 61, this slide having other rack teeth on its upper face engaged by an operating pinion 62 which 55 is formed on a shaft 64. The shaft 64 is provided with another pinion 66 engaged by a gear sector 68 formed on one arm of a bell-crank lever 70 fulcrumed at 72 on the frame of the machine, the other arm of this 60 bell-crank lever, constructed as more particularly hereinafter described, being provided with a roll 74 (Fig. 3) engaged by a cam face 76 on the cam wheel 16. It will thus be seen that through the connections 65 described the jack post 28 is operated to

press the shoe yieldingly against the hold-down 44, the spring 50 being compressed more or less in this operation.

In addition to operating the jack post 28 as above described, the movement of the slide 60 is also utilized to impart rearward movement to the jack and thus to press the heel end of the shoe against a heel band 78, and also to close the heel band inwardly against the opposite sides of the heel end of the shoe. For imparting rearward movement to the jack the bell-crank lever 56 is connected by a link 80 to a pawl carrier 82 provided with a pawl 84 in engagement with a ratchet wheel 86, the ratchet wheel being connected to a pinion 88 which operates a rack bar 90 connected to the holder 24 of the jack, as more fully disclosed in Letters Patent No. 1,583,044. For operating the heel band, as also disclosed in said Letters Patent, the slide 60 acts through a spring 92 upon a rod 94 provided with a cross bar 96 (Fig. 5) in engagement at its opposite ends with rack bars 98, each rack bar being operatively connected with a lever 100 which is connected in turn by a link 102 to an arm 104 provided with means for pressing the heel band against the side of the shoe.

In the use of the machine constructed as thus far described the operator first mounts a last and shoe on the heel pin 30 and then swings the jack rearwardly as far as he can conveniently by hand to carry the shoe into the heel band 78, at the same time raising the jack post 28 to carry the heel-seat face of the shoe against the hold-down 44 by the operation of a treadle (not shown) which acts on the lower end of the rod 32, as more fully disclosed in Letters Patent No. 1,558-737. Thereafter he trips the clutch to start the power operation of the machine. In the normal operation of the machine the cam shaft 18 makes a complete revolution at the end of which the machine is brought automatically to a stop with all the parts in their starting positions. During this operation there is first imparted yieldingly to the jack a rearward movement through the pinion 88 and the rack bar 90 to carry the shoe farther into the heel band by mechanism not herein shown but fully disclosed in Letters Patent No. 1,583,044, and at the same time the hold-down 44 is depressed somewhat to position the heel-seat face of the shoe in a predetermined relation to the wipers. Thereafter the slide 60 is operated to press the shoe still more firmly against the heel band and against the hold-down and also to close the heel band against the opposite sides of the shoe, whereupon the wipers are operated to wipe the margin of the upper inwardly over the heel seat. The wipers are then retracted from over the heel seat and a further movement is imparted to the slide 60 to clamp the shoe still more firmly in

the heel band and also to raise it a little higher than before, the holddown 44 being raised slightly to permit this upward movement of the shoe. A second operative movement 5 is then imparted to the wipers to wipe the upper more firmly over the heel seat, after which the tacks are driven to fasten the upper, the parts of the machine then being returned to their starting positions.

10 At the time of the second operative movement of the wipers it may happen, in case the holddown 44 is so adjusted that the shoe is positioned a little higher than it should be, that the resistance of the shoe to 15 the movement of the wipers will cause the machine to come to a stop without completing its cycle. In that event it has been necessary heretofore for the operator, after releasing the clutch to disconnect the machine 20 from the source of power by the means disclosed in Letters Patent No. 1,583,044, to operate the machine manually through the remainder of its cycle. This, as above stated, is a slow and difficult operation, and 25 involves danger of damaging the shoe or of breaking some part of the machine. To eliminate the necessity for such manual operation of the machine with the disadvantages involved, the machine herein shown 30 is so constructed that the pressure with which the shoe is clamped and held may be relaxed sufficiently to permit the shoe to yield heightwise under the pressure of the wipers and thus permit the machine to complete 35 its cycle automatically. For the purpose in view that arm of the bell-crank lever 70 which carries the roll 74 is made in two parts 106 and 108, the part 106 being integral with the other arm of the lever and 40 the part 108 being pivoted at 110 on the part 106. Normally the two parts of the arm are held in a fixed relation to each other by a latch 112 which is pivoted on the part 108 and is arranged to engage a plate 114 fast 45 on the part 106, the latch being held in operative position by a torsion spring 116. For operating the latch to break the fixed connection between the two parts of the arm there is provided a hand lever 118 fast on a 50 rock shaft 120 which is mounted in a bracket 122 secured to one side of the lower arm of the bell-crank lever 70 and extends through an opening in the lever. The rock shaft 120 carries a pair of cams 124, one at 55 each side of the lever 70, arranged to engage the lower end of the latch 112 and thus to disconnect the latch from the plate 114 when the lever 118 is swung toward the right, as illustrated in Fig. 4. Such movement of 60 the hand lever 118 is effected against the resistance of a torsion spring 126 which acts to return the hand lever to its normal position as soon as the operator releases it, the normal position of the lever being determined 65 by a pin 128 on the bell-crank lever

70 in engagement with one of the cams 124.

It will be understood that when the latch 112 is disconnected from the plate 114 by the movement of the hand lever 118, as above described, the operative connection between the parts 106 and 108 of the upwardly extending arm of the bell-crank lever 70 is broken, so that the cam face 76 no longer has any effect on the lower arm of the bell-crank lever, and consequently the slide 60 70 is released so that the parts controlled thereby for pressing the shoe up against the hold-down and rearwardly against the heel band and for also pressing the heel band against the opposite sides of the shoe are no longer 75 effective to apply any substantial pressure to the shoe. As a result of expansion of the springs 50, 61 and 92 the parts of the bell-crank lever 70 assume a relation to each other such as is illustrated in Fig. 4. Although the shoe is at this time still under control of the means hereinbefore referred to whereby it is pressed yieldingly against the heel band prior to the operative movement of the slide 60, the pressure with which the shoe is held is nevertheless so far relaxed that it is readily yieldable downwardly in response to the pressure of the wipers thereon, and accordingly the machine will immediately complete its cycle of operative 80 movements as soon as the latch 112 is disconnected from the plate 114 as described. Under these conditions the lasting tacks will usually be driven only part way into the shoe, so that they may be readily removed to permit the lasting of the heel end 85 of the shoe to be repeated after proper adjustment of the holddown 44.

The part 108 of the upwardly extending arm of the bell-crank lever 70 is controlled by a torsion spring 130 which tends to return it into its normal relation to the part 106, such return movement being limited by a shoulder 131 on the part 106, and between the two parts a pin and slot connection 132, 100 134 is provided to limit relative movement of the parts out of their normal operative relation and thus prevent danger of excessive strain on the spring 130. By reason of the action of the spring 130 the part 108 is 105 returned automatically into its normal relation to the part 106 as soon as such return movement is permitted by the cam face 76 in the continued operation of the machine, the latch 112 then being returned to its operative holding position by its spring 116. The parts of the mechanism are thus 110 restored automatically to their normal relation to one another without any attention on the part of the operator.

Having thus described my invention, what I claim as new and desire to secure by Letters Patent of the United States is:

1. In a lasting machine, the combination 115 with means for lasting a shoe, of automatic 120

130

- mechanism for controlling the shoe, a portion of said mechanism being displaceable to interrupt its control of the shoe in the event of abnormal resistance of the shoe to the movement of the lasting means.
2. In a power-operated lasting machine, the combination with means for lasting a shoe, of mechanism movable automatically to clamp the shoe after the starting of the power operation of the machine, a portion of said mechanism being displaceable to relax the clamping pressure on the shoe in the event of abnormal resistance of the shoe to the movement of the lasting means.
3. In a lasting machine, the combination with means for lasting a shoe, of a power-driven cam, mechanism operated by said cam for controlling the shoe in the lasting operation, and means for rendering said mechanism ineffective to control the shoe in the event of abnormal resistance of the shoe to the movement of the lasting means.
4. In a heel-end-lasting machine, the combination with heel-lasting wipers movable in an automatically determined cycle of operations of the machine to wipe the margin of the heel end of the upper of a shoe into lasted position, of mechanism constructed and arranged for movement at the will of the operator out of its normal operative position, if the operation of the machine is stopped by abnormal resistance of the shoe to the operative movement of the wipers, to decrease that resistance sufficiently to permit the machine to complete its cycle.
5. In a heel-end-lasting machine, the combination with heel-lasting wipers movable in an automatically determined cycle of operations of the machine to wipe the margin of the heel end of the upper of a shoe into lasted position, of automatic means for controlling the shoe, said means including parts relatively movable out of their normal operative relation to each other after engagement of the wipers with the shoe to decrease the resistance of the shoe to the operative movement of the wipers in the event of abnormal resistance to such movement.
6. In a heel-end-lasting machine, the combination with heel-lasting wipers movable in an automatically determined cycle of operations of the machine to wipe the margin of the heel end of the upper of a shoe into lasted position, of means for clamping and holding the shoe for the operation of said wipers, said means including parts relatively movable out of their normal operative relation to each other, if the operation of the machine is stopped by abnormal resistance of the shoe to the operative movement of the wipers, to relax the clamping pressure on the shoe sufficiently to permit the machine to complete its cycle.
7. In a heel-end-lasting machine, the combination with heel-lasting wipers movable in an automatically determined cycle of operations of the machine to wipe the margin of the heel end of the upper of a shoe into lasted position, of a shoe support and a hold-down arranged to clamp a shoe between them for the operation of said wipers, and mechanism for rendering the shoe support ineffective to maintain the shoe against the hold-down in the event of abnormal resistance of the shoe to the movement of the wipers.
8. In a heel-end-lasting machine, the combination with heel-lasting wipers movable in an automatically determined cycle of operations of the machine to wipe the margin of the heel end of the upper of a shoe into lasted position, of a shoe support and a hold-down arranged to clamp a shoe between them for the operation of said wipers, and automatic means for controlling said shoe support in the normal operation of the machine, said means including parts relatively movable out of their normal operative relation to each other to permit movement of the shoe in a direction away from the hold-down if the operation of the machine is stopped by abnormal resistance of the shoe to the movement of the wipers.
9. In a heel-end-lasting machine, the combination with heel-lasting wipers movable in an automatically determined cycle of operations of the machine to wipe the margin of the heel end of the upper of a shoe into lasted position, of a shoe support and a heel band for positioning and holding the shoe for the operation of said wipers, and mechanism movable at the will of the operator, if the operation of the machine is stopped by abnormal resistance of the shoe to the operative movement of the wipers, to relax the pressure of the heel band on the shoe and to render the shoe support ineffective to maintain the shoe at its normal height.
10. In a heel-end-lasting machine, the combination with heel-lasting wipers movable in an automatically determined cycle of operations of the machine to wipe the margin of the heel end of the upper of a shoe into lasted position, of a jack for supporting the shoe for the operation of said wipers, a hold-down for engaging the bottom of the heel end of the shoe, a heel band for embracing the heel end of the shoe, and mechanism for operating the jack to press the shoe against the hold-down and against the heel band, said mechanism comprising parts relatively movable out of their normal operative relation to each other to relax the pressure of the shoe on the hold-down and on the heel band in the event of abnormal resistance of the shoe to the movement of the wipers.
11. In a heel-end-lasting machine, the combination with heel-lasting wipers mov-

able in an automatically determined cycle of operations of the machine to wipe the margin of the heel end of the upper of a shoe into lasted position, of a shoe support 5 and a heel band for positioning and holding the shoe for the operation of said wipers, and automatic means for controlling said shoe support and heel band in the normal operation of the machine, said means comprising a device connected both to the shoe support and to the heel band and movable at the will of the operator, if the operation of the machine is stopped by abnormal resistance of the shoe to the operating movement of the wipers, to relax the pressure of the heel band on the shoe and to render the shoe support ineffective to maintain the shoe 10 at its normal height.

12. In a heel-end-lasting machine, the combination with heel-lasting wipers movable in an automatically determined cycle of operations of the machine to wipe the margin of the heel end of the upper of a shoe into lasted position, of mechanism including 20 a lever for controlling the shoe, said lever comprising parts relatively movable out of their normal operative relation to each other to decrease the resistance of the shoe to the operative movement of the wipers in the 25 event of abnormal resistance to that movement.

13. In a heel-end-lasting machine, the combination with heel-lasting wipers movable in an automatically determined cycle of 30 operations of the machine to wipe the margin of the heel end of the upper of a shoe into lasted position, of mechanism including a lever movable to clamp the shoe, said lever comprising parts relatively movable out of 35 their normal operative relation to each other to relax the clamping pressure on the shoe if the shoe opposes abnormal resistance to the movement of the wipers.

14. In a heel-end-lasting machine, the combination with heel-lasting wipers movable in an automatically determined cycle of operations of the machine to wipe the margin of the heel end of the upper of a shoe into lasted position, of a shoe support 40 and a heel band for positioning and holding the shoe for the operation of said wipers, and mechanism including a lever for controlling both the shoe support and the heel band, said lever comprising parts relatively 45 movable out of their normal operative relation to each other to decrease the resistance of the shoe to the operative movement of the wipers if the resistance is such as to prevent the completion of that movement.

60 15. In a heel-end-lasting machine, the combination with heel-lasting wipers movable in an automatically determined cycle of operations of the machine to wipe the margin of the heel end of the upper of a shoe 65 into lasted position, of mechanism including

a lever for controlling the shoe, said lever comprising parts relatively movable out of their normal operative relation to each other to decrease the resistance of the shoe to the operative movement of the wipers if the 70 resistance is such as to prevent the completion of that movement, and a device arranged to maintain the parts of the lever in their normal relation to each other but displaceable at the will of the operator to 75 permit their relative movement.

16. In a heel-end-lasting machine, the combination with heel-lasting wipers movable in an automatically determined cycle of operations of the machine to wipe the margin of the heel end of the upper of a shoe into lasted position, of mechanism movable after engagement of the wipers with the shoe to decrease the resistance of the shoe to the operative movement of the wipers if the resistance is such as to prevent the completion of that movement, and automatic means for restoring said mechanism to its normal condition prior to the next 80 operation of the machine on a shoe.

17. In a heel-end-lasting machine, the combination with heel-lasting wipers movable in an automatically determined cycle of operations of the machine to wipe the margin of the heel end of the upper of a shoe into lasted position, of automatic mechanism for controlling the shoe in the normal operation of the machine, said mechanism comprising parts relatively movable out of their normal operative relation to 90 each other, if the operation of the machine is stopped by abnormal resistance of the shoe to the operative movement of the wipers, to decrease that resistance sufficiently to permit the machine to complete its cycle, and automatic means for restoring said parts to their normal relation to each other.

18. In a heel-end-lasting machine, the combination with heel-lasting wipers movable in an automatically determined cycle of operations of the machine to wipe the margin of the heel end of the upper of a shoe into lasted position, of automatic mechanism for controlling the shoe in the normal operation of the machine, said mechanism comprising a lever having parts relatively movable out of their normal operative relation to each other, if the operation of the machine is stopped by abnormal resistance of the shoe to the operative movement of the wipers, to decrease that resistance sufficiently to permit the machine to complete its cycle, a device for normally holding said parts of the lever in fixed relation to each other but movable by the operator to disconnect said parts, and automatic means for restoring the parts of the lever to their normal relation to each other and for returning said device to its holding position.

19. In a machine for operating on shoes,

- the combination with means for operating on a shoe in an automatically determined cycle of operations of the machine, of means displaceable from its normal operative position, if the operation of the machine is stopped by abnormal resistance of the shoe to the movement of said operating means, to decrease that resistance sufficiently to permit the machine to complete its cycle. 70
- 10 20. In a machine for operating on shoes, the combination with means for operating on a shoe in an automatically determined cycle of operations of the machine, of automatic mechanism for controlling the shoe in the normal operation of the machine, said mechanism comprising parts relatively movable out of their normal operative relation to each other to decrease the resistance of the shoe to the movement of said operating means if the resistance is such as to prevent the completion of that movement. 75
- 15 25. In a machine for operating on shoes, the combination with a shoe support, and means for operating on a shoe on said support in an automatically determined cycle of operations of the machine, of automatic mechanism for controlling said shoe support in the normal operation of the machine, said mechanism comprising parts relatively movable out of their normal operative relation to each other to release the shoe support if the shoe opposes abnormal resistance to the movement of said operating means. 80
- 20 30. In a machine for operating on shoes, the combination with means for operating on a shoe in an automatically determined cycle of operations of the machine, of mechanism for controlling the shoe in the normal operation of the machine, said mechanism comprising a lever having parts relatively movable out of their normal operative relation to each other to decrease the resistance of the shoe to the movement of said operating means if the resistance is such as to prevent the completion of that movement. 85
- 25 35. In a machine for operating on shoes, the combination with means for operating on a shoe in an automatically determined cycle of operations of the machine, of mechanism movable after the beginning of the operation of the machine to decrease the resistance of the shoe to the movement of said operating means if the resistance is such as to prevent the completion of that movement, and automatic means for restoring said mechanism to its normal condition prior to the next operation of the machine on a shoe. 90
- 30 40. In a machine for operating on shoes, the combination with means for operating on a shoe in an automatically determined cycle of operations of the machine, of automatic mechanism for controlling the shoe in the normal operation of the machine, said mechanism comprising parts relatively movable out of their normal operative relation to each other at the will of the operator after the beginning of the operation of the machine on the shoe to interrupt their control of the shoe, and automatic means for restoring said parts to their normal relation to each other prior to the next operation of the machine on a shoe. 95
- 35 45. In a machine for operating on shoes, the combination with power-operated means movable to operate on a shoe, of mechanism movable to clamp the shoe in a predetermined relation to said operating means, a portion of said mechanism being displaceable to render the shoe yieldable to the action of said operating means in the event of abnormal resistance to the operation of said means. 100
- 50 55. In a machine for operating on shoes, the combination with means for operating on a shoe, of shoe-controlling mechanism, a cam for operating said mechanism, and means for interrupting the operative relation between said cam and the shoe-controlling mechanism in the event of abnormal resistance of the shoe to the movement of said operating means. 105
- 60 65. In a machine for operating on shoes, the combination with means for operating on a shoe, of a cam and mechanism operated thereby for controlling the shoe, said mech- 110
- 70 75. In a machine for operating on shoes, the combination with means for operating on a shoe, of mechanism movable in an automatically determined cycle of operations of the machine to control the shoe, a portion of said mechanism being displaceable from its normal operative position at the will of the operator after the beginning of the operation of the machine on the shoe to interrupt its control of the shoe. 115
- 80 85. In a machine for operating on shoes, the combination with means for operating on a shoe, of mechanism movable in an automatically determined cycle of operations of the machine to clamp and hold the shoe independently of said operating means, said mechanism comprising parts relatively movable out of their normal operative relation to each other at the will of the operator after the clamping of the shoe to relax the clamping pressure. 120
- 90 95. In a machine for operating on shoes, the combination with means for operating on a shoe, of mechanism movable in an automatically determined cycle of operations of the machine to control the shoe, said mechanism comprising parts relatively movable out of their normal operative relation to each other at the will of the operator after the beginning of the operation of the machine on the shoe to interrupt their control of the shoe, and automatic means for restoring said parts to their normal relation to each other prior to the next operation of the machine on a shoe. 125
- 100 105. In a machine for operating on shoes, the combination with power-operated means movable to operate on a shoe, of mechanism movable to clamp the shoe in a predetermined relation to said operating means, a portion of said mechanism being displaceable to render the shoe yieldable to the action of said operating means in the event of abnormal resistance to the operation of said means. 130

anism comprising parts relatively movable at the will of the operator out of their normal operative relation to each other between the beginning and the end of the operation 5 of the machine on the shoe to interrupt their control of the shoe.

31. In a machine for operating on shoes, the combination with means for operating on a shoe, of mechanism for controlling the 10 shoe comprising a lever having parts relatively movable out of their normal operative relation to each other to interrupt their control of the shoe.

32. In a machine for operating on shoes, 15 the combination with means for operating on a shoe, of mechanism for controlling the shoe comprising parts relatively movable out of their normal operative relation to each other between the beginning and the end 20 of the operation of the machine on the shoe to interrupt their control of the shoe while the machine continues its operations, and means for normally maintaining said parts in a fixed relation to each other throughout 25 the operation of the machine.

33. In a machine for operating on shoes, the combination with means for operating on a shoe, of power-operated cam mechanism for automatically clamping and holding 30 the shoe independently of said operating means, said mechanism comprising parts relatively movable out of their normal operative relation to each other at the will of the operator after the clamping of the 35 shoe to relax the clamping pressure.

34. In a machine for operating on shoes, the combination with means for operating on a shoe, of power-operated mechanism for clamping and holding the shoe automatically 40 for the operation of said means thereon, said mechanism comprising parts relatively movable out of their normal operative relation to each other between the beginning and the end of the operation of the machine 45 on the shoe to relax the clamping pressure, and means normally operative to maintain said parts continuously in their normal relation to each other throughout the operation of the machine but displaceable to permit their relative movement.

35. In a machine for operating on shoes, the combination with means for operating on a shoe, of mechanism for clamping and holding the shoe for the operation of said 55 means thereon, said mechanism comprising a lever having parts normally in fixed relation to each other throughout the operation of the machine but relatively movable out of their normal relation to each other 60 after the clamping of the shoe to relax the clamping pressure if the shoe is improperly positioned.

36. In a machine for operating on shoes, the combination with means for operating 65 on a shoe, of mechanism for clamping and

holding the shoe for the operation of said means thereon, said mechanism comprising a lever having parts normally in fixed relation to each other throughout the operation of the machine but relatively movable out of their normal relation to each other after the clamping of the shoe to relax the clamping pressure if the shoe is improperly positioned, a latch for maintaining said parts in their normal relation to each other, and a member movable to displace said latch from its operative position.

37. In a machine for operating on shoes, the combination with means for operating on a shoe, of mechanism for clamping and holding the shoe for the operation of said means thereon, said mechanism comprising a cam-operated bell-crank lever provided with two pivotally connected parts relatively movable at the will of the operator after the clamping of the shoe to relax the clamping pressure, and a member arranged normally to hold said parts in a fixed relation to each other but displaceable to permit their relative movement.

38. In a machine for operating on shoes, the combination with means for operating on a shoe, of a holddown for engaging the bottom of the shoe, a jack movable to press the shoe against the holddown, a clamping band for embracing an end of the shoe, and a member for controlling both the jack and the clamping band, said member having parts relatively movable out of their normal relation to each other to relax the pressure of the shoe on the holddown and the pressure of the band on the shoe.

39. In a machine for operating on shoes, the combination with means for operating on a shoe, of a holddown for engaging the bottom of the shoe, a jack movable to press the shoe against the holddown, a clamping band for embracing an end of the shoe, a lever for controlling both the jack and the clamping band, said lever having parts relatively movable out of their normal relation to each other to relax the pressure of the shoe on the holddown and the pressure of the band on the shoe, and a device arranged normally to maintain said parts in a fixed relation to each other but displaceable to permit their relative movement.

In testimony whereof I have signed my name to this specification.

JACOB C. JORGENSEN.
